UNITED STATES PATENT OFFICE.

HERMANN BURKHARDT, OF RUESCHLIKON, SWITZERLAND.

FOUNTAIN DRAWING-PEN.

1,374,426.

Specification of Letters Patent. Patented Apr. 12, 1921.

Application filed October 16, 1919. Serial No. 331,165.

To all whom it may concern:

Be it known that I, HERMANN BURKHARDT, citizen of the Republic of Switzerland, residing at Rueschlikon, of the Canton Zurich, 5 of Switzerland, have invented new and useful Improvements in Fountain Drawing Pens, of which the following is a specification.

This invention relates to a fountain drawing pen, the ink receptacle of which can be displaced in an axial direction and is guided in an outer tube. The open upper end of said receptacle is generally pressed by the pen against a plug and thereby closed quite 10 air-tightly, the plug being firmly connected to the above mentioned tube. To the lower end of the ink receptacle, which projects beyond the outer tube, a button is fixed within easy reach of the fingers. If this button is 15 pressed downward, the upper end of the ink receptacle deviates from the aforesaid closing plug, allowing the air to penetrate into the ink receptacle whereby ink is forced into the pen. On releasing the button, the ink 20 receptacle returns to its closing position by the action of a spring.

On the accompanying drawing, one form of the invention is shown, as an example, in—

30 Figures 1 and 2 by two longitudinal sections displaced by 90° one from the other.

Fig. 3 represents a device for regulating the opening of the pen in open position.

Fig. 4 shows a modified form of such a 35 device in two different positions.

Referring now more particularly to Fig. 1, the ink receptacle consists of a lower narrow tube *a* and of an upper wider tube *b* connected to the former by a thread formed 40 on the enlarged head *c* of the tube *a*. The upper tube is guided in an outer tube *d* and can be displaced therein; its upper end is open and a socket *e* is inserted therein, the bore of which is conical at the upper end. 45 An elastic plug *f*, of rubber for instance, fits into this bore and is fixed to the head *g* of tube *d*. The tubular lower part of this head is screwed onto the tube *d* and provided with a lateral opening *h* which brings about at 50 the proper time the communication between the ink receptacle and the atmospheric air.

Between a collar formed by the enlarged head *c* of the lower tube *a* of the ink receptacle and the thickened part *i* of the guide- 55 tube *d*, a compression spring *k* is inserted

which tends to press the ink receptacle upward and against the closing plug.

To the lower part *i* of the tube *d*, a nut *m* is connected by means of a screw socket *l*, said nut carrying the two pen branches *n*. 60 Just below this nut a button *o* is provided for on the receptacle tube *a* and fixed by an adjusting screw. The button *o* projects radially a little beyond the nut *m* and the pen branches *n* and can thus easily be 65 reached by the fingers guiding the pen, especially by the middle finger, without influencing, in any way the holding of the pen.

The normal positions of the ink receptacle, the outer tube *d* and the part firmly connected to that tube is that shown in Fig. 1.

The interior of the ink receptacle is shut off from the admission of air by the plug *f*. Should lack of ink be noticed, the ink 70 receptacle is pressed downward by a pressure on the button against the action of the spring *k*.

This can be done while drawing by the hand guiding the pen. Thereby the ink receptacle passes into the position illustrated in Fig. 2 in which the inserted socket *e* is 75

removed from the plug *f* at the upper end of the ink receptacle; thus a passage is made between said two parts for the air entering 80

through opening *h* (see arrow in Fig. 2). Owing to this admission of air ink can drop 85

from the ink receptacle into the points of the pen. As soon as the required quantity of ink has been admitted, the button is 90

released enabling spring *k* to force back the ink receptacle into the closing position as 95 illustrated by Fig. 1.

Along the lower end of the receptacle part *a* a displacing device provided with a catch member *p* and a collar-shaped spreading member *q*, is guided. By displacing 100 said device the pen branches *n* can be more or less spread apart (see Figs. 3 and 4, position marked in dot and dash lines), thus permitting the branches to be readily cleaned and the thickness of line to be regulated.

Referring now more particularly to Figs. 1 and 3, the aforesaid displacing device slides on the smooth surface of part *a*, while according to Fig. 4 these parts are 105 connected one to the other by a thread.

In the drawing a wire *r* is shown in the lower receptacle part *a*, which wire assists in the removal of obstructions and also in controlling the feed.

Having described the nature of my invention, what I claim as new and desire to secure by Letters Patent of the United States is:—

- 5 1. A fountain drawing pen comprising an ink receptacle guided in an outer tube provided at the top with an opening for the admission of air, and which can be displaced therein in an axial direction and is normally pressed upwardly by a spring so that its upper open end is forced against a closing plug firmly connected to the outer guide-tube, thereby shutting off atmospheric air, said receptacle also carrying a button
- 10 15 within easy reach of the fingers guiding the pen, in such a way that the upper end of the ink receptacle is removed from the closing

plug by pressing the button downward, and said upper end is opened for the admission of atmospheric air.

20

2. Fountain drawing pen according to claim 1, characterized by the fact that the closing plug is formed of elastic material and is fixed to a head which is fitted onto the upper end of the guide-tube, said head being provided with an opening for the admission of air.

25

In testimony whereof I have signed my name to this specification.

HERMANN BURKHARDT.
